BATTERYLESS RINGING DEVICE

William J. Muldoon, Garden City, N. Y., assignor,
by mesne assignments, to The Wheeler Insu-
lated Wire Company, Incorporated, Bridgeport,
Conn., a corporation of Delaware

Application November 22, 1946, Serial No. 711,505

5 Claims. (Cl. 179—87)

1

The present invention relates to signaling de-
vices, and more particularly to a batteryless ring-
ing device for a telephone system.

The development of sound-powered telephone
units has made it possible to communicate over
short distances without the use of external
sources of power. For example, my prior ap-
plication, Serial No. 670,585, describes an inex-
pensive and efficient sound-powered transducer
which is especially suitable for toy telephones,
inter-office telephones, and the like. In such
a system it is desirable to have a ringing unit
and since the telephone system requires no bat-
tery, it is likewise desirable to provide a ringing
unit in which a battery is not required.

Accordingly, the principal object of the present
invention is to provide a batteryless signaling
unit which is especially adaptable for telephone
systems of this type.

In the accompanying drawings, Fig. 1 is an
elevation of a telephone instrument embodying
a signaling unit. According to the present invention;
Figs. 2 and 3 are plan views of the ringing
unit; Figs. 4 and 5 are detail views of the operat-
ing device; and Fig. 6 is a sectional detail view
of the transducer.

The illustrated embodiment of the invention
comprises a ringing unit for a pair of telephones,
here shown as a pair of toy telephones. Each
telephone instrument 2 is provided with a sound-
powered transducer preferably, although not nec-
essarily of the type described in my above-men-
tioned prior application. The unit may be con-
veniently mounted in a hand-set 4 of conven-
tional form.

The ringing system for the telephones com-
prises two synchronous wire reeds 5, one for each
telephone instrument, together with manual
means for vibrating the reed at the transmitting
end, whereby the reed at the receiving end will
be caused to vibrate in synchronism therewith.
Associated with each reed is a bell so arranged
that the receiving reed will strike it and give a
signal. For a toy telephone which is designed to
simulate a standard telephone unit, the reed is
conveniently arranged to be actuated by a rotary
dial 6.

Each telephone instrument has a metal base
3. Mounted on the base is a transducer 10, which
is substantially identical in structure with the
sound-powered transducer described in my prior
application. As shown in Fig. 6, it comprises
two magnets of high coercive force indicated at
12 and carrying between them a magnetic arma-
ture 14. A coil 15 surrounds the armature. The

2

magnets are provided with suitable pole pieces
16 extending into proximity with the armature
near its end. This type of unit is particularly
suitable although any conventional vibrating
magnetic armature type transducer may be used.

The armature 14, instead of being connected
with an acoustic diaphragm, is provided at its
end with an ear 20 having a hole through which
passes the vibratory wire reed 5. As shown in
Figs. 2 and 3, one end of the reed is supported
in a frame 24 and the free end extends out-
wardly into proximity with a bell 26. If the reed
5 is vibrated manually, a current is generated
in the coil 15 of the transducer and thus a signal
is transmitted to the similar unit 10 of the re-
ceiving telephone. The current transmitted to
the receiving unit causes vibration of its arma-
ture and its reed 5, which thereby strikes the bell
and gives the desired signal. The reeds 22 are
preferably of such characteristics that the reed-
armature systems resonate at about 80 cycles per
second, and the two reeds should be tuned ap-
proximately within 5 cycles of each other for
maximum sensitivity.

As heretofore noted, the reed 5 may be vibrated
manually in any desired manner. In a toy unit
the vibration of the reed is preferably initiated
by rotation of the dial 6. It is likewise desirable
to move the bell 26 of the transmitting unit out
of the way of the reed so that the transmitting
reed will not be damped by engagement with its
bell. To these ends, the dial shaft is provided
with a bracket 30 having a portion 32 extend-
ing toward the reed. Pivoted on the part 32 is
a dog 34 which is adapted to engage the reed
upon a clockwise rotation of the dial. The bell
is mounted on an arm 36 pivoted to the base at
38 and normally held by spring 40 against a
stop 42 in the position shown in Fig. 2. As the
dial is turned, the dog 34 moves the bell and
reed to a position as indicated in Fig. 3, at which
point a bracket 44 deflects the reed downward
to a point where further motion of the dog 34
releases the reed. When the dog moves out of
engagement with the reed, the reed snaps back
with a whiplike motion and then vibrates for a
number of cycles. The bell is free to return
under the influence of the spring 40; because
of the high inertia of the bell, however, as com-
pared with that of the reed, the reed will undergo
several vibrations before the bell returns to a
position where the reed will engage with it. Ac-
cordingly, the bell does not damp the reed until
the vibration of the reed is substantially com-
pleted. The electrical signal generated in the

transducer by vibration of the reed is transmitted over the line to the transducer 10 of the receiving telephone, thus causing the reed of the receiving unit to vibrate in unison with that of the transmitter. The receiving reed strikes the bell several times and gives the desired signal.

The electrical connections may be made in any suitable way whereby the transducer units 4 are used for talking and the units 10 for ringing. In most systems and particularly for toy telephones, it is desirable to have a single line connecting both units. The diagram for the preferred simple unit is illustrated in Fig. 2, in which the sound-powered transducer 4 and the reed transducer 10 of a single unit are connected in series. The base of each unit is provided with a terminal block 43 having terminals 44 and 46 to which the line wires 48 and 50 are respectively connected. The coil 15 of the unit 10 is connected between the terminal 44 and a connector 52. As indicated at 54, one side of the coil is grounded to the metal base 3. The acoustic transducer unit is connected between the terminal 52 and the terminal 46 by a suitable cord 56. As heretofore noted, the unit may be mounted in a suitable handset 4 to be carried in the cradle 60 at the top of the instrument.

The connections thus far described place the two acoustic transducers and the two reed transducers of both instruments all in series. Since the toy ringing unit herein specifically described operates at a very low power level, it is desirable to exclude the acoustic transducer 4 of the transmitting telephone from the circuit at the time the ringing operation is being carried out. To this end the terminal 46 is provided with an extension 62 in proximity with the bell. When the bell is swung about its pivot 38 by the dog 34, the extension 62 is engaged by the bell. As shown in Fig. 1, this extension is inclined and is of spring-like material so that it is engaged by the bell for a considerable portion of the ringing cycle. It has been heretofore noted that one side of the coil, corresponding electrically to the terminal 52, is grounded to the base. Thus when the bell engages the contact 62, the acoustic transducer unit 4 is short-circuited. The short-circuit path runs from the terminal 52 through the ground connection 54, the pivot 38, the arm 36, the bell 26 and the contact 62, to the terminal 46. This construction, which is a simple one, results in short-circuiting of the acoustic transducer at the transmitting end during the ringing cycle.

It will be understood that cradle switches operated by the handsets, or similar devices known to those skilled in the telephone art, may be used to short-circuit both acoustic transducers. Such switches would be used in more expensive units but for a toy system the simple means for short-circuiting the transducer at the transmitting end is usually adequate.

In its broader aspects, the present invention comprises an electro-mechanical transducer having a vibrating reed. Two of these units are used, one for each telephone of the pair. The reed which is at the transmitting end is vibrated mechanically. It will be understood that any suitable means may be used for vibrating the reed. For a toy telephone the rotary dial is pro-

vided in order to simulate an actual telephone, and the dial is also conveniently used to vibrate the reed. It will be understood that the energy supplied to the reed for a single operation of the dial is rather small. The invention, however, is not limited to the particular means for setting the reed in vibration, and other means which will maintain the reed in sustained vibration may be preferred for telephones other than toys, as will be clear to those skilled in the art.

Having thus described my invention, I claim:

1. A signaling unit comprising an electro-mechanical transducer having an armature, a permanent magnet and a winding, a vibratory reed connected with the armature, a bell adapted to be struck by the reed, manual means for flexing the reed, and means operated by said manual means for moving the bell out of engagement with the reed during vibration thereof subsequent to such flexing.

2. A signaling unit comprising an electro-mechanical transducer having an armature, a permanent magnet and a winding, a vibratory reed connected with the armature, a bell adapted to be struck by the reed, manual means for manually flexing the reed and for moving the bell therewith out of the range of motion of the reed, whereby the reed when set into vibration by manual flexure, is not damped by the bell.

3. A telephone unit comprising two transducers connected in series, one of said transducers being an acoustic device and the other having a vibratory reed, means for manually setting the reed into vibration to generate a signal, and means operated by said manual means for short-circuiting the acoustic transducer during said period of signal generation.

4. A telephone unit comprising two transducers connected in series, one of said transducers being an acoustic device and the other having a vibratory reed, means for manually setting the reed into vibration, a bell to be rung by the reed, means operated by said manual means to move the bell out of engagement with the reed and a contact engaged by the bell to short-circuit the other transducer.

5. A signaling unit comprising an electro-mechanical transducer having an armature, a vibratory reed connected with the armature, a permanent magnet and a winding, a bell adapted to be struck by the reed, manual means for flexing the reed, and a pivotal mounting for the bell, and means to cause the bell to be swung to a position out of engagement with the reed when the reed is manually flexed.
